CLARENCE J. COBERLY, OF LOS ANGELES, CALIFORNIA, ASSIGNOR, BY DIRECT AND MESNE ASSIGNMENTS, TO KOBE, INC., OF LOS ANGELES, CALIFORNIA, A CORPORATION OF CALIFORNIA

CUTTING TORCH WITH NONINTERFERING CONVERGING JETS

Application filed February 27, 1924. Serial No. 695,476.

My invention comprises a novel type of cutting torch provided with means for projecting a plurality of non-parallel jets of a cutting gas, and it is an especial object of this 5 invention to provide simple and effective means and methods for applying non-interfering jets of the character referred to in the cutting of slots having inclined walls.

It is an object of this invention to provide 10 means and methods for predetermining the inclination of the walls of beveled or relieved slots, and for producing slots either expanding inwardly or expanding outwardly or expanding both inwardly and outwardly from 15 an intermediate plane of constriction.

Other objects of my invention appear from 20 the following description of an illustrative embodiment thereof, and from the appended claims, taken in connection with the accompanying drawings, in which—

Fig. 1 is a vertical or longitudinal section through the tip of a slotting torch embodying my invention and through a plate slotted thereby, this section being taken substantially at right angles to the mentioned slot and in a plane such as is indicated by the line 1—1 of Fig. 4.

Figs. 2 and 3 respectively illustrate alternative types of slot which may be formed by 30 varying the distance between the tip of my novel torch and the work slotted thereby, or by varying the orientation of the torch or tip relatively to said work.

Fig. 4 is a horizontal or transverse section 35 in a plane such as indicated by the line 4—4 of Fig. 1.

Referring to the details of that specific embodiment of my invention chosen for purpose of illustration, 1 may be a plate or other 40 metallic form in which a slot or slots are to be cut; and 2 may be the body or barrel of a slotting torch, which may be of any usual or preferred design, the mentioned body or barrel being shown as provided with longitudinal passages 3, 4, respectively provided for the delivery of oxygen or an oxygen-containing gas and a combustible mixture to a central distributing chamber 5 and to an auxiliary chamber 6, the end of the body or 45 barrel 2 being chambered to receive said de-

livery tip, and provided with means such as the thimble or collar 7 for the retention of the same.

Coming now to the strictly novel features 55 of my invention, I may employ in connection with the elements referred to, a delivery tip provided not only with a passage or passages 8 and 8' leading from the auxiliary chamber 6, for the delivery of a combustible mixture in a manner favorable to the heating of work to 60 be cut, but provided also with a plurality of convergent, non-intersecting passages 9, 9', leading from the distributing chamber 5 and adapted to deliver an excess of oxygen or other cutting gas within an area to be slotted 65 in the manner described, said non-interfering jets being adapted to cooperate in the cutting of a slot having walls whose inclination may depend upon the angular relationship of said jets relative to a plane extending therebetween and longitudinally of said slot. 70

Although the ducts 9, 9' employed for the delivery of an excess of a cutting gas may be of any desired relative inclination, and although alternative tips provided with slots 75 of different inclinations may obviously be substituted at will within an organization of the general character described, I consider it advantageous to employ oxygen-delivery ducts 9, 9' lying in substantially parallel 80 planes, but separated by a distance at least equal to the diameter of the respective ducts; and it will be understood that a single tip of the general character described and shown is capable of use in cutting not only a slot of 85 the character shown in Fig. 1, in the production of which the plane of apparent intersection of the mentioned jets may be maintained at the outer surface of the plate during the slotting of the same, but also in the production of slots having walls more sharply or less sharply inclined, or slots having an intermediate constriction, alternative forms being suggested in Figs. 2 and 3.

For example, by bringing the tip of my 95 novel torch closer to the work, I may form a slot having an intermediate constriction, as shown in Fig. 2; and by bringing said tip still closer to the work and at the same time so orienting the same as to diminish the ap- 100

parent convergence of the cutting jets, as viewed longitudinally of a slot cut thereby, I may produce a slot of the general form illustrated in Fig. 3.

- 5 In connection with the foregoing, it will be understood that the practice of my invention in the cutting of slots having inclined walls implies a relative traversing movement between a torch and the work cut thereby, this traversing movement being effected either by advancing the work or by manipulating the torch, and the means employed for the purposes last referred to being immaterial to the practice of my invention.
- 10 15 It is by the use of a novel torch tip comprising inclined ducts for the delivery of a cutting gas, and by predetermining or varying the distance between such a tip and the work cut thereby, or by suitably orienting the mentioned tip or a torch containing the same during the cutting of a slot, that my novel and advantageous results in the cutting of slots are obtained.
- 20

Although I have herein described one suitable complete embodiment of my invention, it will be understood that various features thereof might be independently employed, and also that various modifications might be made therein without involving the slightest departure from the spirit and scope of my invention, as the same is indicated above and in the following claims.

I claim as my invention:—

1. The method of cutting slots having inclined walls which comprises producing a traversing movement between a body to be slotted and a plurality of non-intersecting jets of a cutting gas inclined relatively to one another, and varying the relative inclination of the walls of said slots by uniformly varying the inclination of said jets relatively to a plane bisecting the angle between said walls.

2. The method of cutting slots having inclined walls which comprises producing a traversing movement between a body to be slotted and a plurality of non-intersecting jets of a cutting gas inclined relatively to one another, and uniformly varying the relative inclination of the walls of said slots by orienting the said jets relatively to a plane bisecting the angle between said walls.

3. The method of cutting slots having inclined walls which comprises producing a traversing movement between a body to be slotted and a plurality of non-intersecting jets of a cutting gas inclined relatively to one another, and varying the character of cut by varying both the distance of said body from a delivery tip and the orientation of said tip.

In testimony whereof, I have hereunto set my hand at Los Angeles, California, this 21st day of February, 1924.

CLARENCE J. COBERLY.
